CLAIM

The ornamental design for a wireless communications repeater, as shown and described.

DESCRIPTION

FIG. 1 is a top view of the repeater;

FIG. 2 is a bottom view thereof;

FIG. 3 is a side view thereof, it being understood that the repeater is symmetric about a vertical axis;

FIG. 4 is a typical side elevation view thereof, taken at a point rotated 30 degrees from the view presented in FIG. 3

FIG. 5 is a bottom perspective view thereof; and,

FIG. 6 is a top perspective view thereof.
